UNITED STATES PATENT OFFICE.

HENRY NEISTADT, OF AMES, IOWA, ASSIGNOR TO THE STANLEY RULE & LEVEL COMPANY, OF NEW BRITAIN, CONNECTICUT, A CORPORATION OF CONNECTICUT.

CLAPBOARD-MARKER.

1,153,171.

Specification of Letters Patent. Patented Sept. 7, 1915.

Application filed January 7, 1915. Serial No. 1,016.

To all whom it may concern:

Be it known that I, HENRY NEISTADT, a citizen of the United States, residing at Ames, county of Story, State of Iowa, have 5 invented certain new and useful Improvements in Clapboard-Markers, of which the following is a full, clear, and exact description.

My invention relates to a marking tool 10 chiefly useful as a clapboard marker, and is essentially an improvement upon the tool set forth in United States Letters Patent No. 344,937, dated July 6, 1886.

The purpose of my present improvement 15 is to provide an attachment for said tool whereby it may be used with greater accuracy, and whereby it is possible to adjust the device so as to mark a clapboard for an easy fit or a driving fit. This and other advantages will be apparent from a reading of 20 the following description.

In the drawings,—Figure 1 is a view of the outer edge of the tool in operative position. Fig. 2 is a side view of the parts 25 shown in Fig. 1 looking from left to right. Fig. 3 is a similar view of the opposite side. Fig. 4 is an end elevation of the tool shown in Fig. 1. Fig. 5 is a relatively enlarged cross-section of the tool shown in 30 operative position.

A represents a plate comprising the main frame, having an appropriate handle and also having two projecting gage-arms b, b at its lower edge.

35 B represents the marking knife, which is preferably serrated along its sharp marking edge, although in all instances this is not necessary. The blade B is secured to one face of the frame A by a screw and slot connection. c, c represent the screws of said screw and slot connection. It will be observed that the cutting or marking edge of the blade B is in the same plane as the working surfaces of the gage-arms b, b. By 40 loosening the screws c, c the position of the blade may be adjusted up and down. The arms at b, b project beyond the marking edge of the blade B. Thus far the parts described correspond with those shown in the 45 above referred to patent.

My improvement comprises an attachment which I may designate as a gage. This gage is indicated at G and preferably comprises a

wooden bar member connected to the frame A by screw and slot connections whereby 55 said gage may be adjusted. The gage-bar G is preferably of substantial thickness, that is to say, it is much greater in thickness than the thickness of the blade B, and along its outer lower edge it is provided with an offset track or working bearings g, which in turn provides a clearance recess H between it and the frame A.

I, I represent the adjusting screws for the gage G whereby it may be raised or lowered 65 to shift its bearing edge g relatively to the plane of the marking edge of the blade B. Ordinarily the gage G should be adjusted to substantially the position shown in Fig. 5, wherein the cutting or marking edge of 70 the blade projects only slightly below the bearing g, so that when the marker is placed in the position indicated in the several figures the frame A will stand at right angles to the clapboard, whereby, as it is moved to 75 and fro, a mark or scratch will be formed across the clapboard to coincide exactly with the edge of the casing against which the end of the clapboard is to bear when in final position.

If it is desired to make a so-called "driving fit" the gage G would be somewhat lowered relatively to the marking edge of the blade B so that, as viewed in Figs. 4 and 5, the tool will be inclined slightly to the right, 85 thus marking a line on the clapboard so positioned that when the clapboard is sawed off on said line it will be necessary to force it into place. The fit may be made easier by raising the gage G relatively to the marking 90 edge of the blade B. It is obvious that this relative adjustment may be effected by adjusting either the blade B or the gage G and it is not therefore essential, although it is preferable, that both of said parts should 95 be adjustable on the frame A.

I have shown in the drawings approximately the working position of the device, in which F represents the end of a strip of clapboard, C represents the lining-boards 100 designed to be covered thereby, and D represents the casing or corner-board against which the ends of the clapboards are to be fitted. In operation, the gage-arms b, b bear against and are guided by the edge of 105 the casing member D while the end of the

clapboard is placed loosely against the face of the casing at approximately the elevation it is to finally take relatively thereto.

What I claim and desire to secure by Letters Patent is:

A marking tool comprising a frame, gage arms carried thereby, a relatively fixed marking blade on said frame having a cutting edge in substantially the plane of the working face of the gage-arms and movable with said frame across the face of a clapboard for marking said clapboard, and a gage bar carried by the frame, provided with a smooth bearing face spaced to one

side of the marking blade for angularly positioning and slidably supporting the tool on the clapboard, said gage bar and cutting edge being adjustable in respect to each other and toward or away from the plane of engagement with the clapboard whereby to incline the tool to one side or the other to cause the cutting edge to mark the clapboard for an "easy" or for a "driving" fit. 15 20

HENRY NEISTADT.
